QUICK BREAKING MEANS FOR ELECTRIC SWITCHES

Wilbur R. Brooks, Hartford, Conn., assignor, by mesne assignments, to Federal Electric Products Company, Inc., Newark, N. J., a corporation of New Jersey

Application March 9, 1942, Serial No. 433,895

6 Claims. (Cl. 200—5)

This invention relates to means for effecting the quick breaking of electric switches. One of the objects of the invention is to provide means for particularly effecting the quick breaking of electric switches of the magnetic motor starter type.

Another object of the invention is to provide resilient means which may be included in not only newly manufactured switch structures but also existing switch structures to effect the quick breaking of a switch of the type actuated by a solenoid whereby, upon release of the solenoid, the movable member of the switch is rapidly moved to open circuit position to effect a quick breaking of the switch.

A still further object of the invention is to provide a spring device which is readily adapted for connection with the interlock structure for a plurality of switches of the magnetic motor starter type whereby a part of the interlock structure is resiliently urged by said spring to effect rapid movement of the movable element of each switch upon release by its solenoid so that quick breaking of each switch is produced when desired.

Other objects as well as details of the invention will be apparent from a consideration of the following specification and the accompanying drawing.

The accompanying drawing shows the embodiment of the invention which is deemed preferable, but it will be understood that the drawing is intended for illustrative purposes only and is not to be construed as defining or limiting the scope of the invention, the claims forming a part of this specification being relied upon for that purpose.

In the drawing:

Fig. 1 is a front elevation of a pair of switches and an interlock connected to the switches, the interlock including springs comprising the present invention.

Fig. 2 is a front elevation of the interlock and springs detached from the switches and the arms disposed in opposite positions to those shown in Fig. 1.

Fig. 3 is a view similar to Fig. 2 with the arms in neutral position.

Fig. 4 is a top plan view of the interlock and springs per se with the various parts in the positions shown in Fig. 1. The legs of the supporting plate are broken to make the view more compact.

Figs. 5 and 6 are respectively front and end

views of the spring per se detached from the interlock.

In the operation of certain types of machines, it is necessary to use a plurality of electric motors. To properly control the functions of these motors, switches are provided, the switches frequently being of the magnetic motor starter type. Furthermore, it is frequently desirable to operate only one motor at a time and in order to 5 insure that other motors will not be concurrently started, the switches controlling the motors are usually mounted adjacent each other and an interlock structure is connected to the switches to insure the closing of only one switch at a time. 10 15 Where such motors, switches, and interlock arrangements are included in certain types of machines, it is sometimes found desirable to effect a quick breaking of the switches in order that the desired functions of the machine may take place 20 and it is to this latter end that the instant invention relates.

The means comprising the present invention for effecting the quick breaking of electric switches primarily consists of a spring member 25 which is mounted so that one free end is engageable with a pivoted interlock arm of an interlock structure, there being one spring provided for each interlock arm. One end of the interlock arm is connected to the movable armature of one of a plurality of switches and the spring member is so designed that it normally urges the interlock arm in a direction to move the movable armature of the switch connected thereto to open circuit position. A solenoid 30 actuates the armature of each switch and, when energized, holds the armature in closed circuit position. Immediately upon the release of said armature by said solenoid however, the interlock arm connected to said armature, by reason of the 35 spring element, quickly moves the armature to open circuit position and effects a quick breaking of the switch.

It is to be understood of course that the invention is not to be restricted to use with interlock structures only or to use with the particular interlock structure described herewith since the invention obviously may be applied to a single switch and the actuating arm therefor. Other 45 50 applications of use are also conceivable and the present illustration and description are primarily for purposes of showing only the preferred embodiment of the invention.

In order that the invention might be fully understood, not only is a description of the

spring elements and the manner of their co-action with the moving parts of the interlock structure given but the operation of the interlock with respect to the plurality of switches engaged thereby is also set forth. No claim is made to the interlock structure per se and its association with the switches in this application since the same forms the subject matter of a separate patent application, Serial No. 430,739, filed February 13, 1942.

Referring to the drawing, each individual magnetic motor starter switch 10 has a thermal relay control unit 12, all of which are mounted on a suitable base plate 14. The respective motor starter switches are provided with a movable contact carrier 16 actuated by an armature 18 movably mounted in the lower portion of the electro-magnetic member 20 which electro-magnetic member serves to actuate the armature 18 to move the contact carrier 16 into engagement with the stationary contact blocks 21.

Each armature is provided with a depending plate 22 which, preferably, is a lamina of the laminae which comprise the armature 18 in conformity with customary construction of such armatures. As clearly shown in Fig. 1, the plate 22 projects below the lower ends of the associated laminae forming the armature 18 sufficiently to afford ample space in which to place an elongated aperture or slot 24 for purposes to be explained. It will be understood that the armature 18 and movable contact carrier 16 to which the armature is connected are mounted for vertical movement with reference to Fig. 1 and such movement is guided by suitable means incorporated in the magnetic motor starter switch structure. Said guiding means, however, does not form a part of the instant invention and therefore is not illustrated.

The mechanical interlock is generally designated 26. The details of the mechanical interlock comprise a supporting member in the form of a mounting bracket 28 which, as viewed in Fig. 4, has downward extending supporting legs 30 having outward extending plates 32 each provided with an aperture 34 by which the mounting bracket may be suitably secured to the base plate 14 such as by a pair of screws 36.

A pair of switch engaging interlock arms 38 are pivotally mounted to the mounting bracket 28 by suitable pivot studs 40 each of which pivot studs is accommodated in a suitable bearing aperture disposed in each interlock arm 38 intermediate the ends thereof. A washer 39 may be placed on the pivot studs between each interlock arm and the mounting bracket to facilitate movement of the interlock arms.

The innermost end of each interlock arm 38 is shaped to form a cam surface 42 angularly disposed to the longitudinal axis of the interlock arm 38. Said end of the interlock arm is also formed with a slightly curved end surface 44 which is substantially a segment of a circle having a radius extending from the pivot stud 40. The curved end surface 44 may be considered a continuation of the cam surface 42 and both surfaces in effect form a composite or continuous cam surface, the curved end surface 44 being in the nature of a dwell on the composite cam surface.

The outer end of each interlock arm 38 is provided with an armature engaging member 46 which is offset upward. The armature engaging member 46 is accommodated in the slot 24 provided in the depending plate 22 on each arma-

ture. The dimensions of each slot 24 are such that they provide free movement therein of the respective armature engaging members 46 without binding in order that the armature may be raised and lowered during actuation thereof by the electro-magnet member 20, and during which raising and lowering the outer end of the interlock arm engaged in the slot 24 will be moved therewith.

An interlocking pin bracket or front guide plate 48 having offset mounting ears 50 disposed at either side is secured to the front face of mounting bracket 28, as viewed in Fig. 1, by screws 52 which extend through suitable apertures in the offset mounting ears 50 and also elongated apertures or slots (not shown) in the mounting bracket 28 and are threaded into locking means hereinafter described. As clearly shown in Fig. 4, the offset between the front guide plate and the mounting ears 50 provides a space between the front guide plate and the mounting bracket 28 to accommodate the inner ends of the interlock arms 38.

The front guide plate 48 is provided medially thereof and adjacent the uppermost edge with a guide slot 56, which guide slot is best shown in Fig. 1 and is for a purpose to be described.

Mounted on the rear or underside of the mounting bracket 28 is an interlock pin guide plate 58 which may be termed the rear guide plate, the same being secured to the mounting bracket by the screws 52 which are threadably received in apertures 60 formed in said rear guide plate to not only secure the guide plate 58 but also lock the front guide plate 48 in operative position. Medially disposed in the rear guide plate adjacent its upper edge, as viewed in Figs. 1-3, is a guide slot 62 which is substantially identical to the slot 56, the slots 56 and 62 being so arranged in the respective guide plates that when said guide plates are assembled as shown in Figs. 1-4, said slots are substantially co-extensive, parallel, and superposed over each other. Said guide slots are held in alignment with each other as just described by the pair of screws 52 which are threaded into the apertures 60 in the rear guide plate 58. When said screws are suitably loosened, the front and rear guide plates may be moved within certain limits as a unit with respect to the mounting bracket 28 by reason of the slots 54 in said mounting bracket.

A locking means illustrated in the form of a cylindrical interlock or locking pin 64 is disposed in a generally rectangular aperture 67 in the mounting bracket 28. The locking pin is provided at opposite ends with cylindrical trunnions 66 which are disposed in the guide slots 56 and 62 of the front and rear guide plates to rotatably mount the locking pin 64 between said guide plates. Obviously the locking pin may not only rotate with respect to the guide plates but the same may also move longitudinally with respect to the same within the limits of the slots 56 and 62. The dimensions of aperture 67 are such that at no time during the movement of the locking pin in any direction will the periphery thereof engage the periphery of the aperture 67.

The locking pin is primarily for the purpose of engaging the angularly disposed cam surface 42 provided on the end of each interlock arm to prevent the inner end of said arm from moving downward and correspondingly prevent the armature engaging member 46 on the outer end of the interlock arm from moving upward whereby the movable contact carrier is also prevented

from moving into engagement with the stationary contact block on one of the magnetic motor starter switches. This function is clearly illustrated in Figs. 1 and 2. The locking pin 64 is held in engagement with the cam surface 42 of one interlock arm by the end surface 44 of the other interlock arm, as is also clearly illustrated in Figs. 1 and 2. The last mentioned interlock arm is held with the end surface 44 against the locking pin by the depending plate 22 on the closed magnetic motor starter switch which holds the outer end of said interlock arm in uppermost position.

With one magnetic motor starter switch thus closed, the second one may not be closed. After said closed switch has been opened however, the armature will drop to its lower position, simultaneously moving the outer, raised end of the engaged interlock arm downward. This will move the inner end of the engaged interlock arm upward and remove the end surface 44 from abutting engagement with the locking pin 64 as viewed in either Figs. 1 or 2, following which, the locking pin 64 may move from locking engagement with the cam surface 42 of the other interlock arm, particularly when the second switch is closed by energizing its electro-magnet 20 to move the armature of said switch upward, which armature simultaneously carries therewith the outer end of the interlock arm 38 engaged therewith and moves the inner end of said arm downward during which movement the cam surface 42 on said arm will force the locking pin 64 toward the inner end of the other interlock arm and into engagement with the cam surface 42 of said other interlock arm to lock its inner end against movement downward and prevent the closing of the switch with which said second interlock arm is engaged.

Assuming both magnetic motor starter switches are open, the interlock arms will then be substantially disposed in the position illustrated in Fig. 3. This position may be termed the neutral position. It will be readily seen that, from this neutral position, the outer end of either one of the interlock arms may be raised by the closing of the switch associated therewith, which action will lower the inner end of the actuated interlock arm and simultaneously force the locking pin away from the outer end of the interlock arm that is actuated and farther into engagement with the cam surface 42 on the inner end of the other interlock arm to hold or lock said inner end of said other interlock arm against downward movement. The end surface 44 of the first interlock arm will, as explained in the foregoing, hold the locking pin 64 in such locking engagement with the inner end of the second interlock arm.

From the neutral position, both switches may not be simultaneously closed since the cam surface of both interlock arms would be caused to engage the locking pin.

The locking pin 64 is preferably rotatably mounted to provide anti-friction engagement between it and the cam and end surfaces 42 and 44 of each of the interlock arms 38.

It will be appreciated that in the mass production of mechanisms by methods used in modern industry, manufacturing variations will exist and items such as magnetic motor starter switches will not always be exact duplicates of each other in that the spacing of certain elements in said switches with respect to certain other elements is not always the same. For example, it has

been found in connection with the development of the present invention that when two magnetic motor starter switches are mounted on a common base plate 14 and both switches are either open or closed, the disposition of the depending plates 22 and the slots 24 therein will not always be the same with respect to a common means on the base plate such as the bottom edge.

To compensate for the above mentioned differences in spacing of the various elements of said magnetic motor starter switches, certain members of the interlock structure comprising the present invention have been made adjustable to permit proper alignment of the armature engaging members 46 with the respective slots 24 through which said armature engaging members project. Such adjustment is afforded by the slots 54 in the mounting bracket 28, which slots permit the vertical movement of the front and rear guide plates 48 and 58. Movement of these guide plates is correspondingly imparted to the locking pin 64 which, in turn, will vary the points of contact upon engagement of said locking pin with the inner ends of the interlock arms 38. After the position of the locking pin has been properly adjusted by so moving the guide plates and the proper position located, said proper position of said guide plates is maintained by tightening the screws 52 into the plate 58. The proper position is such, for example, that when both switches are open, the interlock arms 38 may assume a neutral position similar to that shown in Fig. 3. Similarly, the proper position will also permit one interlock arm to maintain the locking pin in proper locked engagement with the other interlock arm or vice versa to absolutely prevent the closing of one of said switches when the other of said switches is already closed.

The present construction also includes further means for maintaining the proper adjustment of the locking pin with respect to the inner ends of the interlock arms comprising a pair of self-tapping screws 68 which pass through suitable openings in the offset mounting ears 50 on the front guide plate 48. Before inserting said self-tapping screws 68, the mounting bracket 28 is drilled to provide holes therein, using said openings in the offset mounting ears 50 as a templet, following which the self-tapping screws 68 may be threaded into said drilled holes to assist the screws 52 in securing the locking plates in proper position.

The switches illustrated in the foregoing are moved to open position by the force of gravity alone. It is the purpose of the instant invention to provide means whereby said switches may be opened considerably more quickly than the opening by gravity affords whereby a quicker breaking of the switches is obtained.

The structure which comprises the essence of the present invention, namely, the resilient means which urges each of the pivoted interlock arms 38 in a direction to rapidly move the armature 18 connected therewith in a downward direction, is herein illustrated as a substantially U-shaped spring 70. In the preferred embodiment of the present invention, one spring is provided for each interlock arm 38. It is to be understood, of course, that the invention is not necessarily to be so restricted however in that it is conceivable a single spring may be anchored to the structure and be provided with a pair of free ends which are respectively engageable with the interlock arms 38 to urge each of said arms in the desired direction.

As best shown in Figs. 1 through 3, and 6, each spring 70 is formed with one free end 72 bent outward to be received in the space between the guide plates 48 and 58 which also accommodate the ends of the interlock arms having the cams thereon, the spring bearing against the upper edge of the offset portion of the front guide plate 48 to serve as a stop means for one end of the spring. Each spring 70 extends from the offset portion in the front guide plate around the pivot stud 40 and is then bent back upon itself to extend toward the cam end of the interlock arm it is to engage. The other free end of the spring 70 terminates in a substantially U-shaped hook 74, the plane of the hook extending at right angles to the plane in which the remaining portion of the spring is disposed. The U-shaped hook 74 engages the under side of the interlock arm 28 with which it coacts adjacent the innermost end whereby the spring normally urges the inner end of the interlock arm upward and the armature engaging member 46 on the outer end downward whereby the armature with which the member 46 is engaged is constantly urged in a downward direction.

It will thus be seen that immediately upon the release of an armature by the solenoid associated therewith, the spring 70 through the medium of the interlock arm 38 will rapidly move the armature to open circuit position to effect a quick breaking of the switch.

Not only do the springs 70 effect a quick breaking of the switches but, upon the solenoid of a closed switch becoming de-energized, the spring engaging the interlock arm associated with said switch quickly raises the inner end of said interlock arm from engagement with the interlock pin 64 whereby, should it be desired to immediately close the second switch upon the opening of the first, the interlock arm associated with the second switch can quickly cam the interlock pin 64 from out of locking engagement with its inner end without having to first wait for gravity acting on the armature on the first switch to move the first interlock arm from engagement with the interlock pin. In other words, the springs 70 also serve to quickly clear one or the other inner ends of the interlock arms from locking engagement with the interlock pin and in this way a quicker closing of the second switch may be effected following the opening of the first switch.

Ample space is provided for the spring 70 between each interlock arm 38 and the mounting bracket 28 by reason of the washers 39 which are mounted on each pivot stud 40 between the interlock arm and the mounting bracket. In its position of repose, the spring 70 has its outer free ends sufficiently spaced from each other that when said spring is inserted in operative position between the upper edge of the front guide plate 48 and the under side of the interlock arm 38, the tension produced in the spring will be sufficient to rapidly urge the armature engaging member 46 of each interlock arm to its lowermost position in which the switch associated therewith will be in open circuit position. This tension is also sufficient to retain the spring 70 in operative position, the outward bent end 72 engaging behind the offset portion of the front guide plate 48 to retain the spring against movement outward or endwise, away from the pivot stud 40 and the latter prevents appreciable vertical movement of the bight of the spring.

It will be apparent that the spring 70 may be readily connected to the interlock structure in a

number of different ways, one of which consists in temporarily dismounting the interlock assembly from the base plate 14 following which the inner end of each interlock arm may be elevated to permit the U-shaped hook 72 on one end of said spring 70 to be engaged under the lower edge of the interlock arm. The bight of the U-shaped spring 70 is then disposed about the pivot stud 40 and the outward bent free end 72 is snapped into operative position in the space between the guide plates 48 and 58. With the lowering of the inner end of the interlock arm into neutral position such as shown in Fig. 3, the spring 70 will be placed under tension, in which condition it will remain at all times while the interlock is connected to the switches and the base plate.

The rapidity with which the spring 70 moves the interlock arm 38 is determined by the strength of the spring. If more rapid movement and consequent quicker opening of the switch is desired, a stronger spring will be used. Adequate space for various sized springs is provided by the present washers 39 used to space the interlock arms with respect to the mounting bracket 28. If a heavier spring is required than can at present be accommodated, a thicker washer 39 may be used to provide additional space.

It will thus be seen that the springs 70 may be readily attached not only to newly manufactured interlocks but, by the method of insertion described above, the springs may also be expeditiously incorporated in previously manufactured interlock structures of the type described and illustrated as well as any other structures wherein the spring is adaptable.

With the instant invention, the applicant has provided a simple but effective mechanism for effecting a quick break in a switch, and particularly in one of the magnetic motor starter type. The spring means which comprise the essential feature of the instant invention are quickly attachable to interlock structures used in conjunction with a plurality of switches of the magnetic motor starter type and the inclusion of such springs in the interlock structure necessitates no modification or change of the structure of either the interlock or the switches in any way.

While the invention has been illustrated and described in its preferred embodiment and has included certain details, it should be understood that the invention is not to be limited to the precise details herein illustrated and described since the same may be carried out in other ways, falling within the scope of the invention as claimed.

What I claim is:

1. The combination of an electric switch of the magnetic motor starter type having a solenoid actuated movable electric contact carrying member, a base, an arm pivoted to said base and adjacent one end being operatively connected to said movable electric contact carrying member, and a spring having one portion anchored with respect to said base and another portion coacting with said pivoted arm to normally urge the same in a direction to move the movable electric contact carrying member to open circuit position whereby upon release by said solenoid said movable electric contact carrying member is quickly moved by said spring-urged pivoted arm to effect a quick breaking of the switch.

2. The combination of an electric switch of the magnetic motor starter type having a solenoid actuated movable electric contact carrying member, a base, an arm pivoted to said base and

adjacent one end being operatively connected to said movable electric contact carrying member, and a substantially U-shaped spring extending about the pivot of said arm, said spring having one end portion anchored with respect to said base and the other end portion coacting with said pivoted arm to normally urge the same in a direction to move the movable electric contact carrying member to open circuit position whereby upon release by said solenoid said movable electric contact carrying member is quickly moved by said spring-urged pivoted arm to effect a quick breaking of the switch.

3. The combination of a plurality of electric switches of the magnetic motor starter type each including a solenoid actuated movable electric contact carrying member, an interlock adapted to maintain one switch open while the other is closed, said interlock having a base mounted in fixed relationship with respect to said switches and including a plurality of pivotally mounted arms each of which operatively engages one of said solenoid actuated movable electric contact carrying members, and spring means anchored with respect to said interlock base and having movable portions respectively engaging each pivotally mounted arm to normally bias each arm in a direction to urge each movable electric contact carrying member to open circuit position, whereby upon release by the solenoid said movable electric contact carrying member is quickly moved by its respective spring-urged pivotally mounted arm to open circuit position to effect a quick breaking of the switch.

4. The combination of a plurality of electric switches of the magnetic motor starter type each including a solenoid actuated movable electric contact carrying member, an interlock adapted to maintain one switch open while the other is closed, said interlock having a base mounted in fixed relationship with respect to said switches and including a plurality of pivotally mounted arms each of which operatively engages one of said solenoid actuated movable electric contact carrying members, and a plurality of springs each having one portion anchored with respect to said interlock base and another portion engaging one of said pivotally mounted arms to normally urge the same in a direction to move the movable electric contact carrying member engaged therewith to open circuit position, whereby upon release by the solenoid said movable electric contact carrying member is quickly moved by the spring-urged pivotally mounted arm engaged therewith to open circuit position to effect a quick breaking of the switch.

5. The combination of a plurality of electric

switches of the magnetic motor starter type each including a solenoid actuated movable electric contact carrying member, an interlock adapted to maintain one switch open while the other is closed, said interlock having a base mounted in fixed relationship with respect to said switches and including a plurality of pivotally mounted arms each of which operatively engages one of said solenoid actuated movable electric contact carrying members, and a plurality of substantially U-shaped springs each anchored at one end with respect to said interlock base and engaging one pivotally mounted arm with its other end, said springs each also extending about the pivot of the interlock arm engaged thereby and normally urging said pivotally mounted arm in a direction to move the movable electric contact carrying member engaged therewith to open circuit position, whereby upon release by the solenoid said movable electric contact carrying member is quickly moved by the spring-urged pivotally mounted arm engaged therewith to open circuit position to effect a quick breaking of the switch.

6. The combination of a plurality of electric switches of the magnetic motor starter type each including a solenoid actuated movable armature which carries electric contact members, an interlock adapted to maintain one switch open while the other is closed, said interlock having a base mounted in fixed relationship with respect to said switches and including a plurality of pivotally mounted arms each of which operatively engages one of said armatures and also including locking means mounted for movement by one of said pivotally mounted arms to one of a plurality of positions wherein it is held by engagement with said one of said pivotally mounted arms to lock the other pivotally mounted arm and movable armature engaged thereby against movement in one direction when the other movable armature is in closed circuit position, and spring means anchored with respect to said interlock base and having movable portions respectively engaging each pivotally mounted arm to normally bias each arm in a direction to urge each movable armature to open circuit position, whereby upon release of the armature by its solenoid said pivotally mounted arm holding said locking means in said one position is quickly moved from engagement with said locking means to permit said other pivotally mounted arm to move said locking means from locking engagement therewith when it is desired to close the switch to which said second arm is connected.

WILBUR R. BROOKS.
